INVENTOR.

George W. Campbell

BY

D. C. Stickney

ATTORNEY.

UNITED STATES PATENT OFFICE.

GEORGE W. CAMPBELL, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Original application filed June 15, 1918, Serial No. 240,146. Divided and this application filed September 9, 1920. Serial No. 409,076.

To all whom it may concern:

Be it known that I, GEORGE W. CAMPBELL, a citizen of the United States, residing in Hartford, in the county of Hartford and State of Connecticut, have invented certain new and useful Improvements in Type-writing Machines, of which the following is a specification.

This invention relates to margin stops used in connection with line-locking mechanism for typewriting machines, and is a division of my application, No. 240,146, filed June 15, 1918.

I provide lightly constructed margin stops to limit the movement of the carriage in either direction, said stops being stamped and formed out of sheet-metal. Simplicity of construction, lightness and a minimum number of parts are attained.

Other features and advantages will hereinafter appear.

In the accompanying drawings,

Figure 1 is a rear view of an Underwood portable typewriting machine, showing the invention applied thereto.

Figure 2 is a fragmentary front view of the machine, showing the platen displaced for the purpose of positioning the right-hand margin stop.

Figure 3 is a sectional view through the left-hand margin stop (right-hand in Figure 1), showing it assembled on the stop bar.

A carriage 10, comprising the usual paper platen 11, travels on guideways 12 secured to a relatively fixed frame 13. The carriage is moved rightwardly, in Figure 1 which is a rear view, as the typing proceeds, and may be arrested by a margin stop 14 adjustable on a rack-bar 15 at the rear of the machine.

A lever 16, pivoted at 17 on the carriage, engages a projection 18 on the left-hand margin stop 14 to cause the stop-bar to travel with the carriage to lock the type-keys through means including a link 20, as described in said application. The lever 16 is provided with shoulder 21 to engage the projection 18. A key 22 on said lever 16, when depressed, swings the shoulder 21 free of the projection 18 on the margin stop 14 and unlocks the type-keys, so that the carriage may be fed and typing performed after the typist has been cautioned

of the end of the line by the locking of the type-keys. The rack-bar 15 may be pulled back to its normal position, after it is released, by a spring (not shown), this movement being effective to unlock the type-keys.

The carriage may be arrested in its return movement by a shoulder 23, on the lever 16, which engages a projection 24 on a right-hand margin stop 24; the latter being also adjustable on the rack-bar 15.

To adjust the margin stops 14 and 24, each is provided with a finger-piece 25 integrally formed with a C-shaped transversely-movable dog member or slide 26, which has formed thereon a pawl or dog 27 to engage teeth 28 and 30 formed on the stop-bar 15. When the finger-piece 25 is depressed against the tension of a spring 31 and the slide is moved downwardly to disengage the pawl from the teeth of the stop-bar 15, the margin stop may then be moved along said bar to any desired position. The slides 26 are guided in cut-outs 32 formed in the margin stops.

It will be noted that the margin stops may be moved inwardly, or, in other words, toward the middle of the machine, without depressing the finger-piece, the pawls 27 snapping over the teeth 28 and 30 of the bar 15, but the springs are strong enough to hold said stops against accidental displacement inwardly. The margin stops are, however, positively held from being moved outwardly by the pawls 27 abutting against the teeth 28 and 30.

It will be seen that the margin stops are simple in construction and are comprised of light parts which may be readily stamped and bent up from sheet-metal, thus decreasing the cost of manufacture to a minimum.

By an inspection of Figure 2, it will be seen that the front face of the rack-bar 15 is provided with a scale 33 by which the margin stops may be set or located. The right-hand margin stop 24, Figure 3, is provided with a pointer 34. The scale 33 is provided on the front face of the rack-bar, so that it may readily be seen by the operator. Since the rack-bar is located in back of the carriage, the operator moves the carriage to one side or the other when an adjustment of either margin stop is to be made.

The stopping projections 18 and 24^a are

2
inclined so as to allow the lever 16 to ride over them, when the carriage is moved from a position beyond the stops 14 and 24 toward the middle of the machine.

5 Variations may be resorted to within the scope of the invention, and portions of the improvements may be used without others.

Having thus described my invention, I claim:

10 1. In a typewriting machine, the combination with a traveling carriage, of an adjustable sheet-metal marginal stop for limiting the movement of said carriage, said stop having a recess, a toothed bar around which said stop is bent and along which said stop is adjusted, a dog or pawl co-acting with the teeth of said bar for locking said marginal stop against displacement, a C-shaped slide working in said recess on said marginal stop, a finger-piece on said slide for actuating said pawl, said pawl being struck

up from said slide, and a spring for holding said slide in effective position.

2. The combination with a rack having teeth on one edge, of a margin gage comprising a body bent around said rack to slide thereon, said body having on one side a recess, and a movable dog member fitting in said recess, and having a finger-piece whereby it may be depressed to release its dog, and also having a returning spring; said dog member C-shaped in cross-section and comprising one side which lies against said rack within the recess in said body, and also comprising a portion bent around said body opposite said recess; a portion of said dog member at the bend thereof being bent up to form the dog.

GEORGE W. CAMPBELL.
